UNITED STATES PATENT OFFICE.

JOHN H. ELWARD, OF STILLWATER, MINNESOTA.

THRASHING-MACHINE.

SPECIFICATION forming part of Letters Patent No. 268,647, dated December 5, 1882.

Application filed December 27, 1881. (No model.)

To all whom it may concern:

Be it known that I, JOHN H. ELWARD, a citizen of the United States of America, residing at Stillwater, in the county of Washington 5 and State of Minnesota, have invented certain new and useful Improvements in Thrashing-Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 is an elevation of a thrashing and separating machine embodying my improvements, taken from the side opposite to that receiving the power. Fig. 2 is an elevation from the other side, parts of the casing being broken away to more clearly show the interior parts. Fig. 3 is a view on a larger scale of the devices at the rear end of the machine.

In the drawings I have shown the whole of a thrashing and separating machine, many of 25 the parts of which, however, do not pertain essentially to my invention, and therefore need not be here described in detail, though they are indicated by letters, thus:

30 A A' represent the ground-wheels; B, one side of the casing; B', the other side of the casing; C, the feeding table or trough; D, the position of the fan; E, the tailings-elevator; F, the return-spout for the tailings, and G the shaking-shoe.

35 H represents a shaft below the cylinder and parallel to the axis thereof. I is a gear-wheel on said shaft, and J a band-wheel outside thereof. These parts are upon the side of the machine opposite to that receiving power from 40 the engine or horse-power. K is a spur-pinion meshing with the spur-wheel I.

45 L represents the belt-pulley on the end of the fan-shaft; and M is a belt by means of which power is taken to said belt-pulley L from the band-wheel J, there being a belt-tightener employed, if desired, the one shown consisting of a pulley, N, a pivoted arm, O, and an adjustable bar, P.

50 Q is a crank-wheel on shaft H at the opposite side of the machine. It is connected with the bar S by a pitman, R, which bar S reciprocates the separating-table. The shaft H at the end having the crank-wheel Q, is sup-

ported by means of a bracket having a vertical leg, T, attached to the lower sill, and a transverse arm, U, connected to the upright. 55

Outside of the spur-pinion K on the cylinder-shaft are two belt-pulleys, V' V², of which the pulley V' conveys power to the cylinder E' (to be described) by means of a belt, V, and the pulley V² conveys power by another belt to the pulley a of the beater-shaft b. Outside of the belt-pulley a there is a secondary pulley, c, by which power is conveyed from the beater-shaft to the pulley d, which operates the grain-rake. 65

e represents a raddle-belt or tail-rake, mounted upon pulleys or rollers, f. It is supported within a detachable frame, the lower end of which conforms to and is supported against 70 the rear end of the thrashing-machine, it being attached thereto by means of hangers g g. This frame consists of side pieces, h h, and two bottom pieces, i k. The part k of the bottom is connected with the part i by means of springs 75 l l, or otherwise, which are flexible enough to allow the part k to swing downward, but stiff enough to throw said part back and hold it, when the machine is at rest, in the same plane as the part i. This inner part, k, of the bottom 80 is tossed or reciprocated up and down by the following devices:

m is an eccentric mounted on the shaft n of the lower roller of the raddle-belt.

n is a strap surrounding the eccentric m. 85

o is an arm or lever pivoted at or near its center to the side h of the frame. At its upper end it is pivoted to the strap n'. At its lower end it is pivoted to a rod or pitman, p. The lower end of this pitman is mounted 90 loosely in a bearing formed by a block, q, said block being situated somewhat below the springs l l. When the shaft n is rotated for operating the belt e the bar o is oscillated, and this imparts to the part k of the bottom a quick 95 shaking or tossing motion, whereby the grain is discharged from the bottom more freely into the shoe.

The thrashing-cylinder C', with its concave D', operates in substantially the ordinary manner to remove the grain from the heads. With this ordinary cylinder I have combined a secondary cylinder, for the purpose of cutting the straw into small pieces, and devices for feeding and guiding the straw directly from the 105 thrashing-cylinder C' to the cutting-cylinder.

The cutting-cylinder is represented by E', and its concave by F', both being provided with sharp teeth adapted to cut the straw. After the straw has been operated upon by the secondary cylinder it is passed to the beater, which in the ordinary manner operates to distribute it properly upon the separating-table W². The straw after being thus operated upon and passed out of the machine is ready to be packed or stored in any desired manner, it being in such condition as to be adapted for feeding. This is a matter of great importance in many sections of country, and is a great saving in the work and expense of thrashing and preparing straw. The straw is guided from the thrashing-cylinder C' to the cutting-cylinder E' by the grating c', the vertical walls c², and the top d' of the casing, the material passing to the second cylinder through these guiding devices while under the motion imparted to it by the thrashing-cylinder.

W' represents a cut-off, consisting of a board or partition which extends from immediately in rear of the end beater, W, to a suitable point above the separating-table. It is hinged at its upper edge, and at its lower edge is arranged to swing to a limited extent, its downward movement being limited by one or more stops, w. It operates to prevent the air over the separating-table from being thrown forward by the beater toward and beyond the cylinder, this air being heavily charged with dust while the machine is in operation. Its lower end is allowed to swing somewhat, so that it can be elevated sufficiently to permit the passage of any straw that may be carried around by the beater while revolving.

X² (see Fig. 2) is a swinging apron or guard, arranged in rear of the beater and the cut-off W', and adapted to receive straw and grain thrown from the beater, and to hinder or restrain their passage toward the tail end of the machine.

I do not claim broadly an apron or guard arranged in rear of a thrashing-cylinder or beater; but I believe that the combination therewith of a beater and the cut-off W' is new. It may consist of a curtain, a sheet of metal, or board; or it may be composed of a series of round bars or rods flexibly connected with the casing and arranged in parallel lines, horizontal or vertical, in the usual manner. The cut-off will also prevent any grain which may rebound from the guard X from coming in contact with the blades of the beater and being thus shattered.

Heretofore it has been customary to reciprocate the shoe by means of a rod operated by an eccentric on the shaft. The eccentric and its strap, it has been found, require much careful attention to prevent their being cut and entirely destroyed, and even when such attention is bestowed upon these parts they are rapidly worn away, and are a source of constant trouble and expense. I obviate this by means of a simple arrangement of cheaply and easily constructed parts, which are not only

not liable to the impairing agencies which destroy the eccentric and strap, but are also easily replaced if breakage or wear should occur. These devices consist of two levers, X X', the former pivoted to the connecting-bar S between the cranks of the separating-table, and the other, X', pivoted to the part X and to the lower sill of the machine. The rod x, which operates the shoe, is pivoted to the part X'. This latter connection may be adjustable, so as to alter the throw of the rod x, and the pivot x' may also be adjustable, if desired.

I am aware that use has been made of a hinged shield immediately behind the thrashing-cylinder for the purpose of deflecting the upwardly-thrown straw, and insuring that it shall be delivered properly to the separating-table; but I am not aware of the use of a shield constructed and arranged similarly to the cut-off or hinged shield W', which I have shown adapted both to prevent the drawing toward the cylinder of dust-laden air and also to yield to any lumps or masses of straw that may be carried upward by the beater behind which it is arranged.

What I claim is—

1. In a thrashing and separating machine, the combination, with the thrashing-cylinder C' and concave D', arranged to separate the grain from the straw, and the cutting-cylinder E' and concave F', arranged to cut the straw after the separation of the grain, of the guiding devices c' c² d', which conduct the straw to the cutting-cylinder as it is thrown from the thrashing-cylinder, substantially as set forth. 95

2. In a thrashing and separating machine, the combination, with the straw-carrier, having the swinging bottom k, of the shaft n, the eccentrics m on said shaft, and links connecting said eccentrics with the swinging bottom, substantially as set forth. 105

3. In a thrashing and separating machine, the combination, with the thrashing-cylinder, the separating-table, and the beater behind the cylinder and above the table, of the cut-off W' hinged at its upper edge behind the beater, the lower edge arranged in proximity to the beater and adapted to yield upwardly, substantially 110 as and for the purposes set forth. 115

4. The combination, with the beater, the separating-table, and the cut-off W', of the yielding guard X², substantially as set forth.

5. The combination, with the thrashing-cylinder, the separating-table, the beater behind the cylinder and above the table, of the cut-off W', situated behind the beater, and stops arranged, substantially as set forth, to hold the cut-off when in a normal position, inclined toward the beater, the cut-off being hinged to yield upwardly at its lower end, substantially as set forth. 120 125

In testimony whereof I affix my signature in presence of two witnesses.

JOHN H. ELWARD.
